Specification for Design. Patented July 2, 1918.

Application filed November 5, 1917. Serial No. 200,449. Term of patent 7 years.

To all whom it may concern:

Be it known that I, ALICE PAULINE HUBER, a citizen of Switzerland, residing at New York, county and State of New York, have invented a certain new, original, and ornamental Design for Lace, of which the following is a specification.

Said design consists in a lace pattern, as illustrated in the accompanying drawing, wherein is shown a section of a piece of lace in which the figures constituting the characteristic features of the design are shown, in their relative arrangement it being understood that these figures are multiplied

indefinitely in accordance with the length of the piece of lace.

What I claim as new is:

The design for lace as herein shown and described.

In witness whereof, I have hereunto set my hand and seal at New York city, New York this 30th day of October, A. D. nineteen hundred and seventeen.

ALICE PAULINE HUBER. [L. S.]
